UNITED STATES PATENT OFFICE

ALBERT J. TINGLEAF, OF RIVERSIDE, CALIFORNIA, ASSIGNOR OF ONE-HALF TO CARLOS W. MITCHELL, OF RIVERSIDE, CALIFORNIA

STEP CONSTRUCTION FOR LADDERS

Application filed September 25, 1929. Serial No. 395,115.

My invention pertains to a step construction for stepladders, having to do particularly with the support of the step and the binding of the step to the side pieces of the 5 ladder.

An object of my invention is a construction by which the rung or step of a ladder is drawn tight by a tension device against the side pieces of the ladder and at the same 10 time a brace is carried from the step diagonally to the side pieces of the ladder, the tension device and the diagonal brace operating together to form a type of bracket connecting the inside surface of the side pieces and the 15 underside of the step.

Another object of my invention is a ladder having flat steps, comprising utilizing a tension device which exerts a pull longitudinally on the step, drawing the end of the step 20 into close contact with the side pieces and at the same time using a plurality of similar diagonal struts or braces which are somewhat triangular in form and give a support to the bottom of the step and carry the weight borne 25 by the step diagonally to the side pieces. In constructing a stepladder in accordance with my invention I preferably use flat side pieces and flat steps. Bolts having a hook or an eye are utilized to engage a second bolt passing 30 through the step and draw the end of the step into close contact with the side pieces of the ladder. Sheet metal brackets triangular in shape, are utilized underneath the step engaging the second bolt on the step and being 35 themselves attached to a bolt through the side piece below the step. This forms a species of triangular brace or bracket and in which I prefer to utilize a plurality of brackets joined by a common bolt through the side 40 piece below the step.

A further detail feature of my invention therefore comprises a step construction for ladders having a flat step with two bolts therethrough secured to the upper end of two 45 triangular sheet metal brackets. Each of these bolts is caught in a bolt having a hook or an eye shape and drawing the end of the step tight against the side piece. The two metal brackets are flanged and preferably 50 made similar and in lefts and rights; the

lower ends being connected by a common bolt which passes through the side piece of the step.

My invention is illustrated in the accompanying drawings, in which,

Fig. 1 is a perspective view of part of the 55 stepladder;

Fig. 2 is a vertical section through a step of the ladder viewed in the direction of the arrow 2 of Fig. 1, showing the brace brackets 60 in edge elevation;

Fig. 3 is an elevation taken in the direction of the arrow 3 of Fig. 2;

Fig. 4 is a perspective inside view of one 65 of the sheet metal triangular brackets;

Fig. 5 is a perspective view of a hook-shaped bolt;

Figs. 6 and 7 are face views of the straps 70 engaging the heads of the bolts.

In the illustration the side pieces of the 70 ladder are designated by the numeral 11 and the steps by the numeral 12. The side pieces do not have any material cut out therefrom excepting the bored holes to accommodate the bolts and the ends of the steps as indicated at 13 have a butt joint with the side rails of the ladder. The steps are provided 75 with two bored holes 14 through which are inserted the bolts 15, the heads of these bolts bearing on the washer plate 16. Such bolts extend completely through the step.

Tension bolts 17 which are illustrated as having a hook 18 and which are sometimes designated as J bolts, are preferably utilized underneath the step. These bolts have their 85 nuts 19 on the outside of the side rails, the heads bearing on the side washer plates 20. The hook end of the bolt fits around the bolt 15. The triangular brackets or braces designated generally at 21 are preferably formed 90 of sheet metal and have a triangular web 22 with an inclined flange 23. This flange has a lower end 24 which extends slightly beyond the edge 25 of the web and this end is provided with a bolt hole 26. The upper end of the flange is bent substantially horizontally as indicated at 27 and has a bolt hole 28. The upper portion of the web is bent in a partial circle as indicated at 29 and is adapted to extend over the top of the tension bolt 17. The 100

bolts 15 pass through the opening 28 in the end 27 of the flange and through the bolt hole 26 I utilize bolts 30. The heads 31 of the bolts bear on the outside of the side rails of 5 the ladder.

The braces are placed on the ladder so that the edge 25 bears against the inside surface of the side rail and the two brackets are placed so that the edge 32 of the flanges 23 10 are usually bent so that they occupy an angle of slightly less than 90 degrees with the web 22.

It should be noted that the web 22 is disposed at right angles to the planes of the 15 rail 11 and the step 12, thereby furnishing the maximum strength in support of the step. The braces may usually both be made of the same shape and size, thus being made what is termed in lefts and rights. As the lower ends 20 of both of the braces are joined to the same bolt 30, a double triangular brace effect is given to the step. In this case one of the triangles may be considered as formed by the bolts 17 having the upper portion 29 of the 25 web caught thereover and such triangle being bounded by the edge 25 and the flange 23.

Such triangle may be viewed in elevation in Fig. 3, the other triangle is viewed in Fig. 2 in which the upper ends of the braces are 30 spaced apart by the two tension bolts 17 and the bolts 15 and these braces come to a common supporting bolt 30 at the bottom. It will therefore be seen that the latter form of 35 my construction has connecting parts which may be light weight and which give a strong support. It is obvious that the braces and bolts may be placed so that the steps have various inclinations relative to the side rails of the ladder.

40 Various changes may be made in the principles of my invention without departing from the spirit thereof as set forth in the description, drawings and claims.

I claim:

45 1. In a stepladder having a side rail and a step, a triangular shaped brace, an attaching means for fastening the upper end of the brace to the step, a second attaching means for securing the lower end of the brace to the rail, and a third fastening means connecting to the first fastening means and attaching said means to the rail, the said third fastening means also holding the step and the 50 upper end of the brace against the rail.

55 2. In a step ladder having a side rail and a step, a pair of triangular shaped metal braces, each having a lower end connected by a common fastening device to the side rail, bolts connecting the upper ends of each of the 60 braces to the step, a pair of fastening means connecting each of the bolts to the side rails, said latter fastening means holding the end 65 of the step and the upper part of the braces in close engagement with the rail.

65 3. In a stepladder having a side rail and

a step, a triangular shaped metal brace having its lower end secured to the rail, a bolt attaching the upper end of the brace to the step, and a second bolt interconnecting the first bolt and the rail, the said second bolt 70 acting to hold the end of the step and the upper part of the brace in close contact with the rail.

4. In a stepladder having a side rail and a step, a pair of triangular-shaped metal 75 braces, each having a lower end attached to the rail, a bolt securing the outer part of each brace to the under side of the step, a second pair of bolts connecting the first mentioned bolts and the side rail adapted to clamp the 80 step and the upper part of the brace in contact with the rail.

5. In a stepladder having a side rail and a step, a triangular-shaped sheet metal brace with a flange, means securing the lower end 85 of the flange to the side rail, an attaching means securing the upper end of the flange to the underside of the step, and a bolt attaching the second fastening means to the side rail.

6. In a stepladder having a side rail and a step, a sheet metal brace with a triangular-shaped web and a flange at the outer part, means for attaching the lower and upper 90 edges of the flange to the side rail and the underside of the step respectively, a bolt interconnecting the fastening at the upper part of the flange and the rail, and operating to hold the end of the step and the upper portion of the brace in engagement with the 95 rail.

7. In a ladder having a side rail and a step, a sheet metal brace having a triangular-shaped web and a flange at right angles thereto, attaching means for securing the lower end of the flange to the rail, a second attaching means for fastening the upper end of the flange to the underside of the step, a bolt engaging the second fastening means and being connected to the side rail, the web having an extension passing over the said bolt, the bolt being adapted to hold the end of the step and the upper portion of the brace in close engagement with the rail.

8. In a ladder as claimed in claim 7, the step having a plurality of braces, the lower ends of each brace being connected to the side rail by a bolt, the upper portions of the brace being spaced apart and each having a bolt securing same to the rail.

9. In a stepladder having a side rail and a step, a metal plate having the shape of a triangle and disposed at right angles to the plane of the rail and having two of its sides fit flush against the rail and the step respectively, and means to fasten said plate to said rail.

10. In a stepladder having a side rail and a step, a metal plate having the shape of a triangle and disposed at right angles to the 130

plane of the rail and the step respectively and having two of its sides fit flush against the rail and the step respectively, and means to fasten said plate to said rail and said step.

5 11. In a stepladder having a side rail and a step, a triangular shaped brace disposed at right angles to the plane of the rail and the step respectively and having two of its sides fit flush against the rail and the step
10 respectively, means for fastening the bottom angle of the brace to the rail, a second means for fastening the inner angle of the brace to the step, and a third fastening means engaging the second fastening means connected to
15 the rail.

12. In a stepladder having a side rail and a step, a triangular shaped brace disposed at right angles to the plane of the rail and the step respectively, and having two of its
20 sides fit flush against the rail and the step respectively, the free side of said triangular brace being provided with a flange at substantially right angles to the body of the brace, and means to fasten said brace to said
25 rail and said step.

13. In a stepladder having a side rail and a step, a metal plate having the shape of a triangle and having two of its sides fit flush against the rail and the step respectively, and
30 means to fasten said plate to said rail and said step.

In testimony whereof I have signed my name to this specification.

ALBERT J. TINGLEAF.
